US0D1057715S

(12) **United States Design Patent** (10) **Patent No.:** **US D1,057,715 S**
(45) **Date of Patent:** **** Jan. 14, 2025**

(54) **INPUT DEVICES FOR COMPUTERS**

(71) Applicant: **Shigenori Takahashi**, Yokohama (JP)

(72) Inventor: **Shigenori Takahashi**, Yokohama (JP)

(**) Term: **15 Years**

(21) Appl. No.: **29/867,592**

(22) Filed: **Oct. 29, 2022**

(51) **LOC (15) Cl.** **14-02**

(52) **U.S. Cl.**

USPC **D14/356**

CLAIM

The ornamental design for input devices for computers as shown and described.

DESCRIPTION

FIG. 1 is a perspective view of input devices for computers showing the new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

1 Claim, 6 Drawing Sheets
